ANNEALING FURNACE

Clarence B. Hoak, Steubenville, Ohio

Application June 11, 1935, Serial No. 26,049

3 Claims.

(Cl. 266—5)

My invention relates generally to an annealing furnace especially adapted to the heat treating of sheet steel and tin, and particularly to a furnace of this type which applies uniform heat to the top, bottom and sides of the material being treated.

Another important object of my invention is to provide an annealing furnace of the character indicated above in which oxidizing of the material being treated is positively obviated.

Another important object of my invention is to provide an annealing furnace of the character indicated above in which conservation of and effective use of heat and fuel is attained to an unusual degree.

Other important objects of my invention will be apparent from a reading of the following description in connection with the drawings, wherein for purposes of illustration I have shown a preferred embodiment of my invention.

In the drawings:—

Figure 1 is an elevational view of the complete furnace.

Figure 2 is a transverse vertical sectional view through the furnace showing covers and stands used for holding tin plate while the same is being annealed in the furnace.

Figure 3 is a horizontal sectional view taken on the line 3—3 of Figure 2, but with the covers removed from the bases 9.

Figure 4 is a section taken approximately on the line 4—4 of Figure 2, but with the bases and covers omitted, the section being taken through the cover only.

Figure 5 is a perspective view of one of the fuel distributing tile.

Figure 6 is a perspective view of a plate of material to be treated.

Figure 7 is a fragmentary perspective view of a corner of the lower part of one of the stand covers.

Referring in detail to the drawings, the numeral 5 generally designates the cover of the furnace which rests on the base 6 and forms the annealing chamber 7, on the steel floor 8 of which rest the stands which include the legged bases 9, the covers having the side walls 10, the closed top 11 and the reinforcing T's 12, the walls 13, the top 11 and the base 9 forming an air-tight enclosure for the stacked sheet metal 13.

Each of the stands includes a base 9 the arrangement and formation of which is subsequently described herein. Resting on each base 55 is the cover which is of appropriate steel of heat

resisting character and includes the vertical side walls 10, and the closed top which is integral with the upper edges thereof. The side walls are provided with suitably connected vertical T's 12 which taper outwardly and have their widest 5 ends at the lower end of the cover and on a level with the lower end of the cover so as to engage the top of the base 9 and furnish extra support for the side walls, and thereby assist in preventing warping of the side walls which would otherwise take place and cause leaks into the interior of the cover which would militate against perfect sealing of the sheets within the cover.

Attached to the outer edge of the T's is the vertical fence 12' which has its lower edge on 15 a level with the lower edge of the T's and the lower edge of the side walls. This fence is provided as a means to hold sand 11' in position on the base 9 and in proper sealing relation to the lower end of the cover. It will be understood 20 that the sand is so arranged that upon slight warping of the lower edge of the cover the sand will act as an automatic seal to prevent leaks into the interior of the cover. The same construction of cover is utilized if, instead of the 25 two covers shown in the drawings, a single large cover, especially in annealing steel plates, is utilized.

It will be observed that the achievement of heating the material on all four sides at a uniform temperature greatly speeds up the process 30 of annealing and produces a material having a more uniform grain, and all of this is accomplished at a corresponding saving in fuel over present equipment.

The cover 5 comprises the outer shell 14 of steel, lined with insulating material 15 of suitable character. The fuel directing tile 16 may be of carborundum tile or of suitable alloy steel of high heat resisting quality. The top of the 40 tile is beveled as indicated by the numeral 17 to fit the interior of the insulating material 15, and the radially outward side of the tile has an opening 18 near its top and the radially inward side thereof has a fuel outlet opening 19 near 45 its lower end and on a level just below the top of the bases 9 of the stands. The tile 16 define the annealing chamber as well as the four combustion chambers at the radially outward sides of the tile, which combustion chambers are defined by the radially outward side of the tile, the inner side of the insulation 15 of the shell, and some formations in the base 6 to be described. A handle 20 suitably connected to the top of the shell 14 enables lifting the shell into 50 55

place after the sections thereof have been welded together, in order that the shell may be properly placed on the base 6. The bottoms of the tile rest on brick which in turn rest on the 5 inner flange 15' of the bottom of the shell 14. This arrangement of the cover relative to the base enables removing the cover wherever necessary and makes it unnecessary to move the base when it is desired to move or remove the 10 cover for any purpose.

The base which is generally designated 6 comprises the outer cruciform steel shell 21 and lined with suitable insulating material 22 so as to define the combustion chambers 23 which communicate with the bottom of the combustion chambers 24 in the top of the furnace. The centralized steel floor 8 which forms the rest for the stand bases has a central flue opening 26. As disclosed in Figure 2, each chamber 23 has a 20 number of gas burner openings 27 which lead thereinto near the bottom.

The stand bases 9 are of suitable heat resisting material and are spaced upwardly from the platform 8 by legs 28 which permit the heat to 25 pass under the bases and do not in any way prevent the gases from passing to the flue 26.

It may be remarked here that when treating steel instead of tin sheets, and a single large stand and a single large cover is being utilized, although 30 the base is disposed directly over the top opening of the flue 26, the legged base nevertheless provides for free access of the gases to the flue.

It is obvious that the covers 11 which prevent the ingress of gases to the material being treated 35 prevent the oxidation of such material which would render the same useless for certain purposes.

It is obvious that the burning fuel in the combustion boxes 24 enters the top opening 18 in the tile and moving downwardly passes into 40 the heating chamber by way of the openings 19 in the lower end of the tile and then after circulating in the heating compartment passes downwardly and outwardly through the flue 26, passing freely under the bases of the stands on account of the spacing thereof above the platform 8 45 by their legs 28. In this way the top, the sides and the bottom of the pile of sheets 13 is uniformly and continuously heated. The stiffening T's 12 extend at right angles from the side walls 50 of the covers 11 so as to prevent undesired expansion thereof which might permit warping of the covers and permit oxidizing gases to reach the plates being annealed.

Although I have shown and described herein 55 in a preferred embodiment of my invention, it is to be definitely understood that I do not desire

to limit the application of the invention thereto, and any change or changes may be made in the materials, and in the structure and arrangement of the parts, within the spirit of the invention and the scope of the subjoined claims.

5

What is claimed is:—

1. An annealing furnace of the character described comprising a top or cover portion, a base portion, said base portion containing a centralized flue and combustion chamber forming recesses 10 provided with gas burner openings, said cover containing tile walls extending chordally therein and whose radially inward sides define the annealing compartment and whose radially outward sides define the upper part of the combustion 15 boxes registered with corresponding recesses in the base, said tile having openings establishing communication between the combustion boxes and the annealing compartment.

2. An annealing furnace of the character described comprising a cover including a metal shell provided with insulating material, tile walls arranged chordally within said cover so that their radially inward sides define the annealing compartment and whose radially outward sides define 25 combustion boxes, and a base on which said cover rests, said base consisting of a metallic shell having a filling of insulating material, said filling including a centralized flue communicating with the bottom of the annealing compartment and 30 depressions fed by gas burner openings and registering with the combustion boxes, and said tile walls having openings establishing communication between the combustion boxes and the annealing compartment.

35

3. An annealing furnace of the character described comprising a cover including a metal shell provided with insulating material, tile walls arranged chordally within said cover so that their radially inward sides define the annealing compartment and whose radially outward sides define 40 combustion boxes, and a base on which said cover rests, said base consisting of a metallic shell having a filling of insulating material, said filling including a centralized flue communicating with the bottom of the annealing compartment and 45 depressions fed by gas burner openings and registering with the combustion boxes, and said tile walls having openings establishing communication between the combustion boxes and the annealing 50 compartment, the openings in the tile feeding the annealing compartment being at the lower end of the tile, and the openings in the tile in receiving arrangement to the combustion boxes being at the upper end of the tile.
